UNITED STATES PATENT OFFICE

2,496,155

TUBE ICE MACHINE

Archie P. Fulkerson, Louisville, Ky., assignor to
 Henry Vogt Machine Company, Louisville, Ky.,
 a corporation of Kentucky

Application May 13, 1948, Serial No. 26,822

3 Claims. (Cl. 62—105)

1

Tube ice machines as heretofore constructed, as exemplified by the Kubaugh Patent 2,200,424, issued May 14, 1940, include a relatively long freezer unit containing tubes surrounded by refrigerant and through which passes the water to be frozen. The machine is of massive construction, weighing on the order of several tons, and may occupy substantially the full height of the room in which it is installed. For this reason, access to the machine generally requires cutting through the ceiling of the room, or building a pit in the floor below the machine, so that when repairs are necessary the tubes can be removed. In some instances it is not possible to provide the required access space in such manner, or where possible, it adds to the cost of installing the machine.

The present invention has for its object the constructing and mounting of a tube ice machine including a freezer unit above a breaker and water storage unit, so that upon removal of the breaker and water storage unit the freezer unit is accessible for replacement of the tubes. This is accomplished by pivotally mounting the freezer unit on a support, and removably connecting the water storage and breaker unit under the freezer unit. Upon removal of the water storage unit, the freezer unit can be rotated to an inclined position, to thus provide sufficient space to permit removal of the tubes.

The invention will be described in greater detail in connection with the accompanying drawing which illustrates a preferred embodiment of the invention by way of example, and wherein:

Figure 1 is a side elevation illustrating a tube ice machine incorporating the invention, and

Figure 2 is a similar view showing the machine ready for removal of the freezer tubes.

Referring to the drawing, there is provided a supporting frame built up of suitably shaped steel members, and comprising vertical columns 1 supporting transverse beams 2 at the top. Each beam 2 carries a bearing block 3 suitably secured thereto, and providing an arcuate bearing surface 4 of less than 180° in extent flanked by sloping top surfaces 5 and 6. A freezer unit indicated generally at 9 has two brackets 10 built up on its sides, to the bottom of each of which is secured a complementary bearing block 11 providing an arcuate bearing surface 12 not more than 180° in extent, and a sloping bottom surface 13. The bottom surface 14 on the other side of the bearing surface 12 may be horizontal. Two diametrically opposed brackets and bearing blocks are provided, only one being shown in the drawings. A cylin-

2

drical bearing member 15 is located in the complementary bearing surfaces 4 and 12, and the bearing blocks 11, resting on the cylindrical bearings 15, support the freezer unit in substantially balanced relation. A stop 16 coacting with a cross beam 17 prevents rotation of the freezer unit in one direction.

The freezer unit 9 is of the water tube type in which water to be frozen is circulated through the tubes which are surrounded by a refrigerant, such as ammonia. Secured to the bottom of the freezer unit is a housing 18 carrying a cutter or breaker, and a chute portion 19 directs the broken ice to the side, the water draining through a suitable screened opening to the water tank 21. The water is circulated by a pump 22 which draws water from the tank and sends it by pipe 23 to the top of the freezer, the water descending through the tubes. Pipe 23 is bolted to the pump and 20 freezer so as to be easily removable. On the thawing cycle the refrigerant is withdrawn from the freezer through a pipe 24 bolted thereto and connected to a control tank 25 which in turn is connected through a control valve to a reservoir 26 mounted on the frame. A thawing water pipe 27 including a solenoid operated valve is also bolted to the freezer.

When it becomes necessary to gain access to the freezer unit for repairs, the pipe 23 and pipes 24 and 27 are disconnected from the freezer unit. The water tank and cutter assembly then can be removed leaving the freezer unit free to be rotated on the rollers. After removal of a shear plate from the bottom and a cover from the top, the tubes can be withdrawn from either the bottom or top, as required. After making the necessary repairs the freezer unit is restored to its vertical position and pipes 24 and 27 are reconnected, and the water tank and cutter assembly 40 are returned to position, the pipe 23 being reconnected between the pump and freezer. The apparatus is there ready to resume operation.

I claim as my invention:

1. In a tube ice machine: a frame; an upright tube type freezer unit pivotally carried by said frame; a bottom assembly including a water reservoir and ice breaker below the freezer unit and removably secured thereto; and piping removably connected to said water reservoir and freezer unit, whereby upon removal of said piping and bottom assembly the freezer unit is free to pivot to an inclined position.

2. In a tube ice machine: a frame; a pair of bearing blocks carried by said frame, each bearing block comprising an arcuate bearing surface

flanked by sloping top surfaces; a tube type freezer unit; and a pair of brackets extending from said freezer unit, each bracket carrying a complementary bearing block comprising an arcuate bearing surface and at least one upwardly sloping bottom surface, each arcuate bearing surface being less than 180° in extent, whereby the upper bearing block and freezer unit can pivot to an inclined position.

3. In a tube ice machine: a frame; a pair of bearing blocks carried by said frame; each bearing block comprising an arcuate bearing surface having a sloping top on at least one side; a tube type freezer unit having members extending from the sides thereof and supported in said bearings; 15

and a bottom assembly removably secured to said freezer unit.

ARCHIE P. FULKERSON.
